UNITED STATES PATENT OFFICE

FRANCIS MCF. BRINCKERHOFF, OF SUFFERN, NEW YORK, ASSIGNOR TO PRESSED STEEL CAR COMPANY, OF PITTSBURGH, PENNSYLVANIA, A CORPORATION OF NEW JERSEY.

SAFETY DEVICE FOR ARTICULATED CARS.

Application filed May 2, 1927. Serial No. 188,117.

This invention relates to transportation cars, particularly railway transportation cars of the articulated unit type, in which the adjacent ends of two of the bodies of the car are supported upon one truck, and has for an object the provision of means for preventing accidental excessive movement of one of said bodies relative to the other, and for preventing accidental excessive upward movement of one of said ends relative to the other and to the truck, and will thus prevent the accidental separation of said bodies and will tend to maintain both of said ends in connected relation with the truck.

Another object of the invention is to provide means adapted to loosely engage with the adjacent ends of adjacent bodies of an articulated car to prevent accidental separation of said bodies.

A further object of the invention is to provide endless loop means adapted to cooperate with two adjacent bodies of an articulated car unit to prevent accidental separation of said bodies.

A still further object of the invention is to provide an articulated car with removable means for supporting a loop member, which loop member is adapted to engage both of said ends to prevent their accidental separation.

These and other objects will be apparent from the following description.

Referring to the drawings in which like reference characters refer to like parts, Fig. 1 is a plan view of a portion of a railway articulated car embodying the invention, a portion of the view being broken away to more clearly illustrate the invention; Fig. 2 is a sectional view of the same taken on the line 2-2 of Fig. 1; Fig. 3 is a plan view of a portion of a railway articulated car embodying a modification of the invention; and Fig. 4 is a sectional view of the same taken on the line 4-4 of Fig. 3, a portion of the view being broken away to more clearly illustrate the invention.

Referring now in detail to the drawings, the reference character 1 indicates one of the end portions of one body of a railway articulated car unit and 2 indicates one of the end portions of an adjacent body of the car unit, it being understood that the car unit may comprise two or any other desired

number of bodies, and that the connection between any two adjacent bodies is substantially the same as hereinafter fully described.

Depending downwardly from the end portion 1 there is a bearing member 3 having a bearing surface 4 in the shape of a portion of a sphere, and depending downwardly from the end portion 2 of the adjacent body there is a like member 3. The bearing surfaces 4 cooperate with a bearing surface 5 formed on a bearing member 6 on an adjacent truck 7. These bearing members forming a connection between the bodies and truck are described in detail in my pending application for U. S. Patent, Serial No. 176,864, filed March 21, 1927, for articulated car.

Around the outer portion of the bearing surface 5, the bearing member 6 has an upwardly extending flange 8 which is adapted to be engaged by the bearing portions 3, and by such engagement, under normal conditions, the bodies are held against excessive longitudinal or sidewise movement. In the case of a collision or derailment the flange 8 may become broken so that one car body may become separated from the adjacent body, or one or both bodies may become separated from the truck and from each other, and to prevent this I provide a continuous or endless loop 9 which cooperates with two adjacent bodies of the car unit in such a manner that the bodies will not be permitted to become separated from each other. In the present embodiment of the invention, this loop 9 preferably comprises a metallic cable 90, the ends of which are permanently connected together as at 11, but it will be understood that, instead of a cable, the loop may comprise a single integral piece of material. This loop passes around the adjacent bearing portions 3 of both car bodies and is supported upon brackets 12 which brackets are removably secured to curved webs or stops 13 depending downwardly from the end portions of both of the car bodies. The brackets 12 may be of any suitable form, those being illustrated in the preferred form of the invention in Figs. 1 and 2, being in the form of U bolts which are disposed horizontally having their ends passing through the webs or stops 13 and removably secured thereto by nuts or any other removable means. By the use of the removable

brackets it will be seen that the loop may be readily removed from the car bodies or replaced without in any way deforming or destroying the continuity of the loop. When a cable is used it is preferably encased in a tube 14 which is curved and preferably concentric with the curve of the stops 13. This tube is rigid enough so that the loop will not change its shape under ordinary service conditions. It will be noted that there is a slight clearance provided between the loop 9 and the stops 13 which is for the purpose of permitting the bodies to swivel without any binding action taking place between the loop and the stops 13.

It will be noted that under ordinary service conditions the loop 9 rests loosely on the brackets 12, thus permitting relative movement between the loop and the brackets 12. Should a car equipped with the invention be derailed, the center bearing portions of the two adjacent bodies may become separated from the truck bearing member, but the bodies will not become separated from each other due to the loop 9 engaging the stops 13 on the bodies. Should one body move accidentally an excessive distance relative to the other, the loop 9 will engage the stops 13 and the brackets 12, and as the loop is thus in engagement with both bodies, further movement is retarded by the weight of the body that has not moved, thus the bearing portions of the bodies are kept from becoming separated from the truck bearing. In Figs. 3 and 4 a modification of the invention has been illustrated in which one of the car bodies is provided with removable brackets 12 and the adjacent body is provided with integral brackets 15. When it is desired to remove the loop 9 in this modification, the brackets 12 are removed from the one body which will permit the loop to drop downwardly clear of the stop 13. The loop is then moved longitudinally of the car a sufficient distance to be free of integral brackets 15 on the adjacent end of the other car body. The operation of the loop in this modification is the same as that just described in connection with Figs. 1 and 2.

Having thus described the invention what I claim as new and desire to secure by Letters Patent is:—

1. A device for preventing the separation of the adjacent ends of two bodies of an articulated car comprising a member cooperating with both of said bodies, and removable means for supporting said member.

2. A device for preventing the separation of the adjacent ends of two bodies of an articulated car comprising loop means loosely engaging both of said bodies, and removable means for supporting said loop means in its operative position.

3. In an articulated car comprising a plurality of car bodies, a one piece safety loop cooperating with the adjacent ends of two of said bodies for preventing the accidental separation of said ends, said loop being freely movable relative to both of said ends.

4. A device for preventing the separation of the adjacent ends of two bodies of an articulated car comprising an endless member adapted to loosely engage both of said bodies.

5. In an articulated car comprising a plurality of car bodies having body bearings and a truck bearing, a curved stop on the end portion of each of said bodies, and a loop adapted to engage the stops on said bodies to support the loop which is adapted to prevent the separation of said ends.

6. In an articulated car comprising a plurality of car bodies, a curved stop on the end portion of each of said bodies, and a loop adapted to engage the stops on said bodies to prevent the separation of said ends, and removable means on said stops for supporting said loop.

7. In an articulated car comprising a plurality of car bodies, downwardly depending stops on the end portions of adjacent car bodies, horizontally disposed brackets removably mounted on said stops, and a member loosely mounted on said brackets adapted to prevent the separation of said ends.

In testimony whereof I affix my signature.

FRANCIS McF. BRINCKERHOFF.
